UNITED STATES PATENT OFFICE.

EBON FRANK NASH, OF MOUNT CARMEL, OHIO, ASSIGNOR OF ONE-THIRD,
TO WILLIAM F. POND, OF MOUNT CARMEL, OHIO.

FEEDER FOR CORN HUSKERS AND SHREDDERS.

No. 818,549.

Specification of Letters Patent.

Patented April 24, 1906.

Application filed February 1, 1904. Serial No. 191,591.

To all whom it may concern:

Be it known that I, EBON FRANK NASH, a citizen of the United States, and a resident of the village of Mount Carmel, in the county 5 of Clermont and State of Ohio, have invented certain new and useful Improvements in Feeders for Corn Huskers and Shredders, of which the following is a specification.

The several features of my invention and 10 the various advantages resulting from their use, conjointly or otherwise, will be apparent from the following description and claims.

In the accompanying drawings, making 15 part of this specification, and in which similar letters of reference indicate corresponding parts, Figure 1 is a view in perspective of mechanism illustrating my invention. Fig. 2 represents a side elevation of the same mechanism. Fig. 3 shows in side elevation 20 mechanism that in certain particulars show a modification of a certain feature of my invention. Fig. 4 is an elevation showing the preferred means for rotating the spreader and for sustaining the latter. Fig. 5 is a view in 25 perspective of the spreader.

A indicates that part of the frame of the machine which is the principal immediate support for the mechanism to be described.

B indicates the shredder-head, provided 30 with knives B², each radial row being set in a cylinder, but preferably upon a disk B³, there being as many disks as there are rows of knives. This head revolves in the direction of the arrow B⁴, Fig. 2.

C C² are the snapping-rolls. Roll C is of 35 larger diameter than roll C². These rolls respectively rotate in the direction of the arrow marked on them. (See Fig. 2.) Both rolls are fluted or corrugated in the direction 40 of their length.

The journals B⁵ of the shredder and the respective journals C J and C J² of the snapping-rolls C and C² are suitably supported. A preferred means for this purpose consists 45 of the two end bearing-pieces D D, one of which, respectively, supports said journals at each side of the machine. The bearings of the upper journals of the upper snapping-roll are, so movable under spring-pressure that 50 they will allow the roll C to separate from the roll C² sufficiently to permit a requisite amount of stalks to enter between them; but this spring-pressure is sufficient to enable these rolls to thoroughly snap all of the ears

from the stalks as the ears approach these 55 rolls and also to fully break up and crush the stalks as the latter, divested of the ears, pass between them, (the rolls.) The preferred means for conferring this elastic pressure consists of a spring D² compressed between the 60 bearing of journal C and the upper end of the piece D. This spring is preferably held in position by the screw-bolt D³. Thereby this spring can be more or less compressed and the pressure upon the bearing be increased or 65 diminished. Of course above the bearing C B of the journal C the piece D is slotted at D⁴. The combination of the journal C, bearing C B, spring D², bolt D³, with slot in piece D, is repeated at the other side of the ma- 70 chine. In front of these snapping-rolls C C², I locate a carrier E. This carrier is inclined, with the end E² lower than the line where the rolls C C² meet each other. Thus the stalks with the ears of corn are compelled to ascend. The upper side E³ of this carrier is 75 preferably, as shown, in a plane which if extended would coincide with the plane between these two rolls. The journals of these rolls C and C² are preferably in a plane substan- 80 tially at right angles to the plane of the upper side of the inclined carrier E. This carrier E is practically a broad endless belt or a series of parallel belts. This carrier has teeth or spikes E⁴, whose free ends incline relatively to the plane of the carrier-belt. Thus on the upper side E³ of the carrier the free ends of these spikes incline toward the lower end E² of the carrier. On the under side of 85 the carrier these free ends obviously incline in a reverse direction. The object in having these teeth thus inclined is to prevent them from carrying the fodder back, as only a small part of the free ends of the teeth contact with the fodder, so that this contact is immediately 90 broken when the teeth begin to pass down over the top roll of the carrier. This would not be so if the teeth stood up at right angles to the plane of the carrier, for in this case the whole tooth would contact with the fodder, 95 and this contact would not be broken by the teeth passing over the roll, so that some of the fodder would be carried down with the carrier.

Between the upper end of the carrier E and 100 the snapping-rolls C C² is a space S, into which the ears of corn snapped from the stalks can and do fall and pass down and out

of the way and to a proper place where they can be collected for future use. As the ears fall out of the way full opportunity is afforded the stalks to pass between the rolls C C² and be duly broken, crushed, and bruised.

To accommodate properly the varying sizes of grain, I make provision for correspondingly varying the width of the space S, and my preferred construction to accomplish this object is as follows: The endless belt of the carrier is stretched between and rotates on rollers H and K. Roller H is journaled in bearings H², one at each side. Roller K is journaled in bearings K², one on each side, and slides in a slot K³ in a fixed part K⁴, a screw K⁵ in part K⁴ serving to move said bearing. The parts H² and K⁴ are secured on or made integral with a channeled piece H³, sliding on the frame-piece M. This piece H³ is slotted at H⁴, through which slot a bolt H⁵ passes into the frame-piece M, so that by tightening this bolt the piece H³ is held immovable on the frame M. When it is desired to increase the width of the space S, the bolts H⁵ are loosened and the channeled piece H³ moved toward the left in Fig. 1. This movement draws the carrier E farther to the left and increases the width of the space S. To decrease the width of the space S, these aforementioned manipulations are reversed. It will be understood that duplicates of the channel-piece H³ and of its attached parts are provided on the other side of the device. On each side for convenience the frame-piece M extends below the main frame A and also above the latter as far as the apex M³, where it meets piece M⁴, and thus forms a strong truss. Braces N at various points serve to strengthen the frame structure and render it rigid.

P represents thin rods having their lower ends secured to the cross-bar P², which is carried by the frame. These rods extend over the carrier E and are parallel therewith. These rods assist in keeping the stalks parallel as to length with the length of the carrier E, and hence in the right position to enter between the snapping-rolls C and C².

A horizontal carrier Q is present, supported by the rollers Q² Q³, and by the rotation of these it is operated. The rollers Q² Q³ are duly journaled, the roller Q² in journal-bearing Q⁴ and the roller Q³ in journal-bearing Q⁵. The latter is adjustable by means of the screw Q⁶ in the manner already illustrated and specified in the matter of the parts K², K³, K⁴, and K⁵. This screw Q⁶ enables the carrier to be kept as taut as desired.

It will be understood that the stalks are fed endwise to the machine. The function of the spreader is not to turn them, but to push the upper ones to the center, so that the stalks shall be spread out and cover the carrier instead of being piled up at any point.

The preferred construction of the spreader

R is illustrated in Figs. 1, 2, 3, and 5. It consists of two screw or spiral plates meeting at the center of the spreader.

In practice the spreader is turned in the direction of the arrow. (See Fig. 3.) Such rotation causes the stalks to be moved by the threads or plates of the spreader from the center toward the side edges of the carriers. The stalks thus spread fall between the fingers P and by the latter are kept in line as they (the stalks) are conveyed to the snapping-rolls C C². As the height (thickness) of the bunch of stalks introduced between the spreader and the inclined carrier varies in almost every instance, the spreader is adapted, through its connections, to be capable of being lifted so as to allow these bunches of varying thickness to pass beneath it. To this end the spreader is mounted on an axle R², whose ends are journaled, respectively, in bearings R³, each fixed to the lower end of its adjacent rod R⁴. The upper end of each of these rods R⁴ are formed with an eye or sleeve R⁵, which is pivoted upon a rod R⁶, supported on brackets on the uprights R A. The spreader R has a rotary movement that is positive. This movement is communicated to the spreader through the gear R⁷ concentric therewith, and this gear is duly connected with a gear R⁸, driven from a suitable source. The preferred means of connecting these gears R⁷ and R⁸ is by a sprocket-chain R⁹. In such event these gears will be sprocket-gears.

Any suitable means may be employed to prevent the spreader from dropping too low. One preferred means consists of a slot R¹⁰, formed in the side board of the machine (shown in Fig. 4) and adapted to receive the axle R² of the spreader. There will be one of these slots at each end of the spreader. As the gears R⁷ R⁸ are usually located outside of the side board of the machine, the slot R¹⁰ enables the axle of the spreader passing through said board to be raised or lowered without any interference.

The preferred mode of supporting the frames already mentioned is the long frame A, that supports the inclined frame M, and the truss-pieces M² N, &c., and the uprights R A, substantially as shown. This frame A is also preferably utilized to support the horizontal carrier Q. When desired, a modification may obtain—to wit, a close union of the inclined carrier and the horizontal carrier. These may be formed as one, the horizontal portion being indicated by the character QX and the inclined carrier by the character EX. The frame M may be modified, the upper portion MX remaining. The spreader R will preferably be located at the junction of the portions EX and QX of the carrier. It is to be understood that the fingers P are to be present with the modified mechanism shown in Fig. 3.

One of the principal advantages obtained from the inclination of the carrier is a marked reduction of the amount of corn shelled. In feeding the stalks up his inclined carrier to the snapping-rolls the rear ends of the ears as they advance are below the line of the snapping-rolls. When the ears reach the snapping-rolls and are snapped or broken off, the ears fall back and away from the rolls and readily pass down between the snapping-rolls and the adjacent end of the carrier in readiness to be husked either immediately by the husking-rolls or in a separate machine. The inclination of the carrier efficiently prevents the ears from coming into contact with the snapping-rolls. I am thus enabled to utilize the force of gravity to assist me in this desirable object of keeping the ears intact at this step in the operation. I thereby prevent much corn from being shelled by the snapping-rolls that would otherwise be shelled off and which is so shelled when the carrier is horizontal.

It is to be noted that in most of the machines of the class for which my invention is adapted a husking device or husker lies directly below, and then as the ears of corn fall in the space between the snapping-rolls on the one hand and the end of the carrier at the other they enter the husking device and are there duly operated upon.

A great many slight changes might be made in the general form and arrangement of the parts described without departing from my invention, and hence I do not, therefore, confine myself in each instance to the precise details set forth, but consider myself at liberty to make such slight changes and alterations as fairly fall within the spirit and scope of my invention.

What I claim as new and of my invention, and desire to secure by Letters Patent, is—

1. In a feeder for corn-huskers, the combination of the inclined carrier, the snapping-rolls at the upper end of the carrier, rollers for supporting the carrier, means for rendering one of these rollers adjustable relatively to the other, bearings for said rollers, channeled pieces H³ for supporting the bearings, a frame M on which the channeled pieces are adapted to slide, said pieces H³ having slots therein and bolts on, and above the frame M engaging in the said slots so that by tightening the bolts the pieces H³ will be locked to the frame, substantially as described.
2. In a feeder for corn-huskers, the combination of an inclined frame M, an inclined carrier, snapping-rolls adjacent the upper end of the carrier, a shredding mechanism in rear of said rolls, rollers for supporting the carrier, channeled pieces H³ supporting the bearings of said rollers, means for adjusting the bearings of one roller relatively to the bearings of the other roller, a frame adapted to support the said snapping-rolls and the said shredder, said frame being supported by the inclined frame M, and means for enabling the pieces H³ to be adjusted nearer to or farther from said snapping-rolls, substantially as described.

3. In a feeder for corn-huskers, the combination of the snapping-rolls, the inclined carrier adjustable to and from these rolls, rollers H, K, supporting the carrier, means for slidably supporting said rollers, the horizontal carrier, rollers Q² Q³ supporting the same, the roller Q² being supported by a part of the inclined carrier so as to have movement therewith, and means for the adjustment of the roller Q³.

4. In a feeder for corn-huskers, the combination of the snapping-rolls, the inclined carrier adjustable to and from these rolls, rollers H, K, supporting the carrier, means for slidably supporting said rollers, the horizontal carrier, rollers Q² Q³, supporting the same, the roller Q² being supported by a part of the inclined carrier so as to have movement therewith, and means for the adjustment of the roller Q³, and a spreader located just beyond the rear end of the horizontal carrier.

5. In a feeder for corn-huskers, the combination of the snapping-rolls, the inclined carrier adjustable to and from these rolls, rollers H, K, supporting the carrier, means for slidably supporting said rollers, the horizontal carrier, rollers Q², Q³, supporting the same, the roller Q² being supported by a part of the inclined carrier so as to have movement therewith, means for the adjustment of the roller Q³, a cross-bar located below the adjacent ends of the two carriers, a plurality of rods having one end held by said rod and extending above and parallel with the inclined carrier, the other ends of said rod being free, and a spreader located just beyond the rear end of the horizontal carrier.

EBON | FRANK NASH.
